UNITED STATES PATENT OFFICE.

JAMES THOMAS HARRISON, JR., OF SAPPHIRE, NORTH CAROLINA.

PNEUMATIC SHOE.

Application filed March 16, 1923. Serial No. 625,554.

To all whom it may concern:

Be it known that I, JAMES THOMAS HARRISON, Jr., a citizen of the United States, and a resident of Sapphire, in the county 5 of Transylvania and State of North Carolina, have invented certain new and useful Improvements in Pneumatic Shoes, of which the following is a specification.

This invention relates in general to an 10 improvement in pneumatic shoes, and more particularly to an improvement in shoes having a cushioned ground engaging surface which may include a pneumatic sole or a pneumatic heel or both.

15 The object of the invention is to provide a shoe of this character which is durable, which is attractive in appearance and yet at the same time has easy walking properties in that it absorbs all shocks and strains 20 while enabling the user to have a firm and easy tread when walking or running.

Other objects and advantages of the invention reside in certain novel features of the construction, combination and arrangement 25 of parts which will be hereinafter more fully described and particularly pointed out in the appended claims, reference being had to the accompanying drawings forming part of this specification, and in 30 which:

Figure 1 is a view, partly in elevation and partly in vertical section, showing the preferred embodiment of the invention;

Figure 2 is a bottom plan view with the 35 lower wall or side of the sole removed; and

Figure 3 is a view on line 3—3, of Figure 1.

Referring to the drawings wherein for the sake of illustration is shown the preferred 40 embodiment of the invention the numeral 10 designates the shoe which includes an upper 11 which may be constructed in any conventional manner of leather, rubber or canvas. The sole which is designated generally at 12, includes a piece or inner ply 13 of leather or other material designated at 14 which is stitched or suitably secured to the upper. To this inner ply 13 an outer 45 ply or casing 14 of rubber, leather or other flexible material is secured as by stitching or the like and this casing 14 is shaped to the contour of the sole and heel and is sufficiently large to provide a space 15 between this casing and the ply 13. In the part of 50 the shoe wherein the heel is located a block 16 is arranged so that the space 15 is of

practically uniform area throughout. In the portion of the space 15 comprehended by the sole of the shoe and in the portion of the space comprehended by the heel of the shoe a multiplicity of transversely extending tubes 17 are provided. The tubes 17 are arranged in two series, as shown in Figure 2, one along each side of the shoe and are separated along the center line of the sole by a small space 18. The ends of the tubes confronting the space 18 are open but the ends of the tube which lie against the vertical portions of the casing 14 are closed and secured to such vertical portions as by means of glue or other suitable fastening means. Moreover the tubes 17 are secured along their tops and bottoms by cement or suitable fastening means to the 60 ply 13 and casing 14, respectively, as indicated at 19 and 20 respectively. At a suitable point the casing 14 is provided with an 65 inflating valve 21 which may be of suitable or conventional construction. The tubes 17 are preferably made of flexible material 70 preferably inelastic but which may have some limited degree of elasticity if found desirable.

In use the space 15 contains air under pressure which fills the tubes 17 and this 75 gives to the sole cushioning properties which relieves the user of the shoe of all shocks in walking and which at the same time enhances the traction between the ground engaging surface of the shoe and the ground. 80 Moreover the sole is of durable construction and of neat and attractive appearance. An important feature of the invention is thought to reside in the arrangement of the tubes 17 and the manner in which they are 85 related to the other elements of the invention in that they are secured along their tops and bottoms to the ply of leather 13 and casing 14 and it is this feature that holds the parts of the pneumatic sole 90 against deformation when inflated and at the same time strengthens and increases the efficiency of the entire device.

I claim:

1. A shoe having a pneumatic sole including a casing secured to the bottom of a shoe and containing air under pressure and a series of tubes arranged in the casing, one along each side of the shoe, the tubes being spaced along the center of the 105 casing and having their confronting ends open and their remote ends closed, said tubes 110

being secured along their tops and bottoms to the bottom of the shoe and to the casing respectively.

2. A shoe having a ply constituting a bottom and a pneumatic sole comprising a casing secured to said ply and spaced therefrom to define an air-tight compartment containing air under pressure, series of tubes arranged in said space, one such series being arranged along each side of the sole, the tubes having their confronting ends slightly spaced and open and having their

remote ends closed, the tops and bottoms of the tubes being secured to the ply and the casing respectively, and an inflating valve 10 carried by the casing.

3. A pneumatic sole having an air-tight compartment therein and containing air under pressure and a plurality of tubes arranged in the compartment, the interior of 20 the tubes communicating with the compartment, said tubes being secured to the opposite walls of the compartment.

JAMES THOMAS HARRISON, JR.
